ABSTRACT

Photographic methods are disclosed whereby raw film is exposed, developed and projected to obtain a quantity of motion picture film which is only a fraction of that normally used to view the same photographed field. One method comprises producing successive, anamorphic images on a raw film which are compressed in only one direction with substantially no spacing existing between successive images and then developing and printing the raw film to obtain positive film having similarly sized images. Another method comprises producing successive, anamorphic images on a raw film which are compressed equally in two perpendicular directions with substantially no spacing existing between successive images and then developing and printing the raw film to obtain a positive film having similarly dimensioned images.

REDUCED-SIZE MOTION PICTURE FILMS AND THE PHOTOGRAPHING AND PROJECTION THEREOF

This is a continuation of application Ser. No. 515,092, filed Dec. 20, 1965, now abandoned.

The present invention relates to photographic processes whereby tremendous amounts of motion picture film and related materials may be saved as compared to conventional processes.

In previous practice, the standard frame dimensions for a 35 mm. film, for example, have been 22×16 mm., on which photographing and projection have been accomplished.

Such practice has required vast quantities of film and the silver contents thereof in photographing and printing motion picture films. In addition, the related labor costs have been enormous for such workers as cameramen, assistants, projection engineers in the motion picture theater, carriers of raw film and motion picture and other films, repairers of motion picture film, supervisors of various films in storage, and so forth, with the result that the accumulated labor cost and the ever increasing space for storing the films have placed the motion picture industry in a financial predicament. These disadvantages, are in fact daily aggravated by the current trend of the motion picture industry toward longer films and wider screens.

An object of the present invention is to provide a new half-size motion picture film to adequately improve the aforementioned defects of the motion picture industry.

Another object of the present invention is to provide a method of manufacturing and projecting the half-size motion picture film.

Another object of the invention is to provide a photographic process for producing wide screen pictures with a saving of one-half the amount of film normally expended on wide screen pictures.

This invention provides a motion picture film which is a continuation of frames having sizes which are vertically reduced by one-half as compared with the standard size and wherein the number of frames driven per unit time is equal to that of the standard-size motion picture film while the driven quantity of the film is designed to be one-half of the standard size.

Furthermore, the half-size motion picture film provided by the invention is a continuation of frames vertically reduced by one-half of the standard size and also with the sound-recorded part as one-half of the standard size moreover, the number of frames driven per unit time is equal to that of the standard-size motion picture film while the driven quantity of the film is designed to be a half of the standard-size motion picture film.

The half-size motion picture film involves the photographing and restorative projecting system based on anamorphous images and the photographing and projecting system based on slightly anamorphous or right images.

The invention provides a method of photographing and projecting by means of the half-size motion picture film, which method comprises the exposure of raw film by the use of an anamorphous optical system in order to obtain anamorphous images reduced by one-half in size in the vertical direction (including the horizontally reduced images by the anamorphous lens) as against the horizontal direction of the photographed scenes, the development of such film to produce a negative which is a continuation of frames with vertically reduced images formed on each frame, the printing of the negative to produce the positive, and the projection of right images on the screen by the use of an anamorphous optical system of the projector so that the obtained images may be extended and restored in inverse proportion to the reduced anamorphous images. This motion picture film can be viewed not on the so-called wide screens but on the standard-size screen.

Moreover, the invention provides another method of photographing and projecting by means of the half-size motion picture film, which method comprises the exposure and photographing of the motion picture film by the use of a certain optical system in order to obtain right or slightly anamorphous images, i.e., undistorted images on the film

reduced by one-half in size in the vertical direction, the development of the film to produce a negative vertically reduced film on which right or slightly anamorphous images are formed, and the obtaining of wide or standard-sized motion pictures from the images on the film thus obtained by means of a certain optical system.

The reverse film may be used in the photographing and projecting of the motion picture film of the invention which is a continuation of the compressed or reduced images. In this case, the positive film may be obtained immediately through development after photographing, with the otherwise required intermediate process of printing from the negative to the positive being omitted.

In relation to the photographing and projecting of each type of the above-discussed half-size motion picture film, the following machinery is found to be preferable and required.

Such machinery contains a half-size motion picture film photographing equipment which mainly consists of means to feed raw film, a system of kinematographic lenses, a mechanism equipped with an intermittent raking claw of a stroke reduced by one-half as compared with the standard camera, and an aperture vertically reduced to one-half of the standard size, in order to take the vertically reduced images compared with the standard size on raw film.

Such machinery also contains a half-size motion picture film projector which consists of a projecting mechanism and a sound-regenerating mechanism which handle the motion picture film with images vertically reduced to one-half of the standard size. The projecting mechanism comprises a system of projecting lenses, a driving mechanism with the same number of revolutions of the film-driving sprocket as the standard projector and with one-half the number of teeth on the sprocket as compared to the standard projector, and an aperture region with apertures vertically reduced one-half in size. The sound-regenerating mechanism comprises a driving means with its film-driving speed reduced by half and a slit mirror with the width of the slit being one-half the normal size.

However, the sizes of motion picture film now in prevalent use are 35 mm., 70 mm., or 16 mm., so that it is considered to be especially desirable to provide a changeover type of projector which can use both the standard motion picture film and the half-size motion picture film of the present invention.

Details of the objects, constructions, features, performances, and effects of this invention other than described above will be clarified in the following explanation made with reference to the accompanying drawings wherein:

FIG. 1A and FIG. 1B are front elevation views respectively of the motion picture film of this invention and the standard motion picture film given in comparison;

FIG. 2 and FIG. 3 are side elevation views of photographing and projecting lenses, respectively;

FIG. 4 is a side elevation view of an anamorphous lens for horizontal compression combined with the system of lenses in FIG. 2;

FIG. 5 is a schematic view of the motion picture camera;

FIG. 6 is a sectional view of a part of the movement of the same camera;

FIG. 7A and FIG. 7B are sketch diagrams showing other examples of the intermittent action of the raking claw in the movement of the camera;

FIG. 8A and FIG. 8B are comparison views of the aperture of the camera;

FIG. 9A and FIG. 9B are comparison views of the aperture of the projector;

FIG. 10 is a sketch diagram of the recording device;

FIG. 11 is a front elevation view of another embodiment of the motion picture film provided by the invention;

FIG. 12 and FIG. 13 are side elevation views of other embodiments of photographing lenses and projecting lenses, respectively;

FIG. 14A and FIG. 14B are explanatory views of the projection of the motion picture film of this invention and the standard film, respectively;

FIG. 15, FIG. 16 and FIG. 17 are respectively a side elevation view, a front elevation view, and a rear elevation view of the projector;

FIG. 18 is a front elevation view of the mask plate at the aperture of the half-size projector;

FIG. 19 is a face view of same;

FIG. 20 is a sectional view taken along line XX-XX of FIG. 18;

FIG. 21 is a front elevation view of the mask plate at the aperture of the standard-size projector given as a contrast;

FIG. 22 is a face view of same;

FIG. 23 is a sectional view taken along line XXIII-XXIII of FIG. 21;

FIG. 24 through FIG. 28 are front elevation views of the motion picture film of the invention in different sizes;

FIG. 29 and FIG. 30 are front elevation views of the motion picture film of the invention on different reduced scales;

FIG. 31 is a side elevation view on the gearbox side of the head machine, with its lid open;

FIG. 32 is a side elevation view on the film-driving side of the head machine;

FIGS. 33 and 34 are explanatory diagrams of each gearbox mechanism;

FIG. 35 is a circuit diagram of the transmitting and receiving synchronism;

FIGS. 36 through 39 are explanatory diagrams of each example;

FIG. 40 is a schematic diagram of the sound-regenerating changeover mechanism;

FIG. 41 is a side elevation view of the upper recording regeneration mechanism without its lid;

FIG. 42 is a front elevation view of the oil box;

FIG. 43 is a sectional view of the said oil box taken along Xliii-Xliii;

FIG. 44 is a front elevation view of another example of the part of magnetic regenerating head;

FIG. 45 is a plane view of the sound wheel;

FIG. 46 is a side elevation view of another example of the upper recording-regenerating mechanism.

For convenience sake, first the following description is given for the motion picture film carrying reduced images of objects or scenes. The illustrated embodiment is one-half the standard size.

Referring now in detail to the drawings, there is shown in FIG. 1 an example of the motion picture film 1 of the invention in 35 mm. (This is to be repeated in the following.) 1' shows the standard motion picture film in conventional use. The motion picture film of the present invention differs from the standard one in that a single frame of the former has two perforations compared with four perforations of the latter, and that the dimensions of an image 2 of the half-size film are 22×8 mm. compared with the standard 22×16 mm. 1a is the recording zone, also reduced by half in size. (An optical recording zone is illustrated here, but a magnetic recording zone is also applicable.) It should be noted that the spacing existing between successive frames of the images 2 shown in FIG. 1A of the film of the present invention is the same as the spacing between successive frames of the images shown in FIG. 1B of a standard motion picture film. This is manufactured by photographing on a film objects or scenes reduced by half vertically, that is, perpendicularly to the horizontal direction. For example, the camera is loaded with a 35 mm. raw film. An exemplary system of photographing lenses is shown in FIG. 2. L1, L2, L3, L4 and L5 give a system of cylindrical lenses, which serve to reduce the vertical dimensions of the original object to half of the horizontal dimensions. L6, L7, L8, L9, L10, L11, and L12 show an ordinary system of spherical lenses, in combination with which the cylindrical lenses are used to effect exposure on the above-mentioned raw film. The subsequent system of lenses shown by L6, L7, L8, L9, L10, L11 and L12 may be had by combining the spherical lenses now in use.

The film thus exposed is developed into a negative film which is a continuation of frames with substantially no spacing between successive frames and on which anamorphous images vertically reduced by half are recorded. The negative is then treated by a well-known method to produce a positive motion picture film 1 likewise having no spacing between successive images.

Now we are going to explain the principle underlying the projection by the use of this motion picture film.

FIG. 3 gives a system of projecting lenses of the projector, which restores and projects the vertically reduced images on the viewing screen. L1, L2, L3, L4 and L5 are a system similar to the system of cylindrical lenses of FIG. 2, while L6, L7, L8 and L9 are a system of spherical projecting lenses, which restore the vertically reduced anamorphous images in inverse proportion and project the right images on the screen. The system of lenses, L6, L7, L8 and L9, subsequent to the above projecting lenses, may be had in proper combination of any spherical projecting lenses now in use.

Apart from the above-described ordinary application, a completely opposite phenomenon occurs if the present invention is employed in conjunction with the wide-angle photographic (Cinemascope) by the use of anamorphous lenses to effect horizontal compression. To be more specific, the original object or scene may be horizontally reduced in half dimensions by means of the system of cylindrical lenses conventionally used for horizontal compression, as shown by L'1, L'2, L'3, L'4 and L'5 of FIG. 4, while at the same time the image thus compressed is vertically reduced by means of the above-mentioned preceding system of cylindrical photographing lenses shown by L1, L2, L3, L4 and L5.

The image thus obtained is, as explained previously, an image with vertical and horizontal dimensions reduced by half of the original, encompassing the right image in as wide a scope as may be had by the conventional anamorphous lenses for horizontal compression. Previously the projection of the horizontally compressed images has been accomplished by using in combination spherical projecting lenses and anamorphous cylindrical lenses, but this invention enables projection to be made only by the use of wide-angle projecting lenses (spherical lenses), since the images obtained are right images of reduced dimensions and with a comparatively large focal depth. In case the wide-angle projecting lenses are not used, it is sufficient to combine the above-mentioned projecting lenses (FIG. 3) with the anamorphous lenses.

The following is a detailed description of the machines employed in the photographic process of the present invention.

FIG. 5 shows the essential parts of the camera of the invention. FIG. 6 is an enlarged, fragmentary, sectional view of the intermittent movement of the camera. FIG. 8 is a comparison view of the aperture exposure device. FIG. 8A shows the exposure aperture of the camera of the invention; FIG. 8B shows the exposure aperture of the conventional camera. The aperture 2a of the invention, corresponding to the frame 2 of the film in FIG. 1, has the same horizontal dimensions but half in vertical dimensions as compared with the conventional exposure aperture 2b.

In FIG. 5 and FIG. 6 a camera box 119 contains a mechanism of movement consisting of a raking claw 5, a registration pin 53, and so on, and behind the mechanism and on the side of the box is provided a housing which contains gears and a motor to drive the movement mechanism, the front side of the box being equipped with a lens cylinder 118 containing photographing lenses as shown in FIG. 2 or FIG. 4, while the upper face of the box is equipped with a magazine 108.

The above movement mechanism is shown in greater detail in FIG. 6. A registration pin-driving shaft 100, projecting from said gear housing into the box 119, has the same number of revolutions as the conventional one, and a gear 101 secured to said shaft 100 is equipped fixedly with a registration pin driving cam 105 in ordinary eccentric fashion, said cam 105 being engaged with a cam follower 104 provided in a rod 125 of said registration pin.

A gear 102, installed to a raking-claw driving shaft 3, engages with said gear 101, which is provided fixedly with a raking-claw driving cam 4 in half the eccentricity of the conventional case, and a cam follower 103 provided on a rod 51 of said raking claw is engaged with said cam 4. Therefore, on rotation of the cam 4, the raking claw 5 performs an elliptic movement with its major and minor axes reduced by half of the conventional case. A bearing block 124 supports the other end of the rod 51 so as to permit free sliding motion and is installed to the box 119 so that it may rotate freely. The other end of the rod 125 is freely supported by another bearing block 126.

An aperture plate 114 is provided with an exposure aperture half in size shown in FIG. 8A. 115 and 116 are respectively a registration plate and a pressure plate.

A shutter 117 is the same as the conventional one in its shape and number of revolutions.

A film-driving sprocket 106, secured to the shaft protruding from inside the above-mentioned gear housing, has the same number of revolutions as the conventional one, with its diameter reduced by half of the conventional type so that the speed of driving the film into the above-mentioned movement mechanism may be reduced by half. 107 is a guide roller.

Feed rollers 109, 110 and 111 inside the magazine 108 have the conventional number of revolutions, but their diameters are reduced by half so that the film feed speed may be reduced to one-half of the conventional one. A film-taking-up roller 113 has its diameter also reduced by half so as to decrease the taking-up speed by half compared with the conventional one. 112 is a film-supporting roller.

Properly reduced revolution is imparted from the shaft 120 of the motor via a gear train 121 to said sprocket 106 and shaft 100, while on the other hand revolution is imparted via a gear train 122 to the roller 109, from which revolution is further transmitted to the rollers 110 and 111, the taking-up roller 113 being rotated by the roller 110 through a belt 123.

Previously the camera has fed a film at the driving speed of 27.4 m. per minute, with four perforations per frame. Since the present invention provides a frame having two perforations, as has been explained earlier, if it is desired to feed 24 frames a second as in the previous case, the film-driving speed has to be 13.7 m. per minute, which is half of the previous speed.

In the camera of this invention, the rotating speed of the rollers 109, 110 and 111 and the sprocket 106 is half of the previous type, so that the film is driven from the magazine into the movement mechanism at a speed of 13.7 m. per minute. Then the raking claw 5, having its vertical stroke reduced by half, intermittently rakes down two perforations per frame at a speed of 24 frames/second. Correlatively the registration pin 53 reciprocates 24 times a second intermittently at the same speed as the conventional type, fixing the film at the exposure position for a given exposure time with a frame having two perforations exposed at a time. The exposed film is taken up by the taking-up roller 113 through the sprocket 106 and the roller 109.

Apart from the above-mentioned method of changing the mass of eccentricity of the cam, there is another embodiment of this invention in which the feed of the film is changed from four perforations to two perforations. In other words, with the mass of eccentricity of the raking claw driving cam 4 kept the same as the conventional type, the major axis of the curve 7 of the elliptical motion (the curve of intermittent motion) of the raking claw may be decreased to the half of the conventional length by increasing the length from the shaft 3 to the bearing 124 of the rod 51 properly as shown in FIG. 7A. FIG. 7B gives a conventional case compared with FIG. 7A, with the figures and letters denoting the parts corresponding to those of this invention.

With the diameters of the sprocket 106 and the rollers 109, 110 and 111 remaining the same as the conventional ones, the film-driving speed may be changed to 13.7 m./min by changing the reduction ratio of the gear trains 121 and 122 from the

motor shaft 120 or decreasing their number of revolutions by half by means of proper reduction gears. In this case, however, since it is necessary to maintain the feed in the movement at the conventional rate of 24 frames/second, the number of revolutions of the shaft 100 has to be adjusted in conventional fashion. The number of revolutions of the shutter has also to be adjusted to that of the movement.

The recording method may be similar to the previous one which is provided with a means to feed the film, a magazine to receive the recorded film, a driving means to progress the film, a microphone, and a modulator to effect various modulations to a recording lamp by giving various sound electric currents led from the microphone through said modulator to the lamp. FIG. 10 shows a sketch diagram of the slit part of the optical recorder for ready comprehension. 127 is the mirror holder, 128 is the mirror and 129 is the slit.

The width of the slit is normally 40 mil, but it is reduced to half, namely, 20 mil in this invention. The normal slit mirror may be detachably provided with a metal tape with the slit of 20 mil for either use to the recordings by conventional method or the invention.

Now we proceed to introduce the motion picture film with shortened images as different from the film with compressed images as in the first example described above. This is another application of our half-size proposal.

This motion picture film is manufactured in the following manner, and a motion picture can be produced from this film.

First of all, the above-described camera is loaded with a raw film of given dimensions, a 35mm. raw film in this case.

FIG. 12 shows the system of photographing lenses for said motion picture film to be provided in the lens cylinder of this camera. L1, L2, L3, L4, and L5 are a system of wide conversion lenses and L6, L7, L8, L9, L10, L11, and L12 are a system of spherical lenses. (A system of lenses subsequent to these photographing lenses, shown by L6, L7, L8, L9, L10, L11 and L12, may be had by combining the spherical photographing lenses normally used at present). In other words, this is an example of the composition of a system of wide conversion lenses. By means of this combination of lenses, the film vertically reduced by half is exposed to light. The image thus obtained is not only of the Cinemascope type, but also is a right or slightly anamorphous image. In addition, it is also possible in this case to use a system of spherical photographing lenses (in any type of combination) instead of the above-mentioned system of wide conversion lenses. Whether or not the system of wide conversion lenses is used, it is found in practice to be satisfactory and convenient to use a system of spherical photographing lenses of about 50 mm.

If the film thus exposed is developed, there will be produced a negative film which is a continuation of frames having right or slightly anamorphous images which are formed on the vertically shortened film surface. The desired motion picture film is obtained if the positive film is made of said negative film by the ordinary method. Since this motion picture film provides the right images or the images slightly anamorphous to a practically negligible extent, it is also adaptable to the uses which involves no projection on the screen. FIG. 11 shows said motion picture film 1. It is similar to that shown in FIG. 1A except that the obtained image is the right or slightly anamorphous image.

Now the system of projecting lenses used in projecting images of this motion picture film on the screen will be explained. FIG. 13 shows systems of projecting lenses, namely, L1, L2, L4 and L5 are a system of wide conversion lenses and L6, L7, L8 and L9 are a system of spherical projecting lenses, through the combination of which and by restoring and projecting on the viewing screen the images on the film vertically shortened by half through the aperture reduced half in size, a motion picture is presented to the audience with the same effect as in the ordinary motion picture. In this case, it is also possible to use an ordinary system of projecting lenses (in any desired combination) instead of said system of wide conversion lenses. Moreover, whether or not the system of wide con-

version lenses is used, the effect on the screen will be accentuated if a combination of lenses approximately 75 to 100 mm. is used in order to remove anamorphous aberration. The other details are similar to those of the first embodiment.

Now in the 35 mm. wide screen projecting system, objects are photographed as images horizontally reduced by half so that one frame may contain four perforations, and for projection, the image is enlarged double horizontally with an anamorphic attachment provided before the standard lenses, as shown in FIG. 14B, resulting in horizontally lengthened images at an aspect ratio of 1:2.35. This invention, however, has such features and effects that photographing is made without the use of the anamorphic attachment so that horizontally long images having an aspect ratio of 1:2.35 may be formed in a frame with two perforations, and for projection, again without the use of the anamorphic attachment, as shown in FIG. 14A, only the standard system of projecting lenses can be used to accomplish a wide screen projection having an aspect ratio of 1:2.35.

A more concrete explanation of the projector of this invention will be given in reference to FIGS. 15 to 17. In FIGS. 10 to 13, a frame 19, an aperture 20, a shutter 21 and a lens cylinder L, and a lamp house La are the same as the conventional ones. The lens cylinder contains combinations of lenses so that it may be possible to use at will a system of cylindrical lenses L1, L2, L3, L4 and L5 combined with a system of spherical projecting lenses L6, L7, L8 and L9 in case anamorphous images are formed on the film, or a system of wide conversion lenses L1, L2, L4 and L5 combined with a system of spherical projecting lenses L6, L7, L8 and L9 in case right or slightly anamorphous images are formed on the film. An upper drum sprocket 62 has previously had 16 teeth, raking down four perforations of a frame for every 90° intermittent rotation (four teeth), while in this application of the invention, one frame is designed to have two perforations, so that the diameter of said sprocket has to be reduced by half in size with eight teeth for 90° intermittent rotation (two teeth). According as the sprocket has been reduced in size, the press roller has to be replaced with one having correspondingly reduced dimensions. Similarly to the case of the aforementioned camera, the film feed speed is reduced from the previous 27.4 m./min. to 13.7 m./min. by reduction gears or any other similarly functioning device. However, again similarly to the camera, the film intermittent feed remains at the same rate as the conventional 24 frames per second, necessitating the means of intermittent motion and the rotation of the shutter to be adjusted to the conventional 24-frame projection. Accordingly, it is possible, as an example, to maintain the 24-frame projection by doubling the worm gearing ratio of the cam shaft of the maltese cross and the shutter shaft. The film-driving speed in the recorder is also decreased to 13.7 m. per minute.

The half-size motion picture film is withdrawn into the projector through the upper magazine by means of said upper drum sprocket 62 having half the standard number of teeth, and passes through a film gate 65 having a guide roller 63 and pressed by a film band 64. The passing of the film through the film gate 65 is intermittently driven at a rate of 24 times per second by means of the intermittent sprocket 66 having half the standard number of teeth. As shown in FIG. 9A, the rays of light that have passed through the aperture with an area half of the standard aperture irradiate the film and project images on the screen by means of the projecting lens cylinder L. The film, passing through the intermittent sprocket 66, is continuously driven by the lower drum sprocket having half the standard number of teeth. Thus no modification has to be made in the inner mechanisms of the projector, but only the number of teeth of each sprocket is to be reduced to half of the standard number to enable the half-size 35 mm. film to be projected on the screen. The film, having passed through this projector, is fed into the lower regenerating mechanism. The film is pressed to a sound wheel 69 by a guide roller 68 while being continuously driven by means of a constant speed sprocket 70,

and is further fed into the lower magazine by means of a hold-back sprocket 71. In the portion of the sound-regenerating mechanism where the film passes, standard parts are used except that the number of revolutions of each sprocket is half that of the standard one and the width of the slit of the slit lens 72 is half that as the standard one. The constant speed sprocket 70 and the holdback sprocket 71 are driven by shafts 72' and 73. The rotating power of a motor M, part of which is omitted in the illustration, is imparted to a pinion 76 through a flywheel 74 and a coupling 75, driving gears 77 and 78 connected to the shaft 72' and the holdback 73. The shaft 72 drives the constant speed sprocket 70 and simultaneously a gear 79. The gear 79 engages with a gear 80 which rotates idly around the shaft 73, and another sprocket 81 is connected to the gear 80. The other end of the shaft 73 is provided with the holdback sprocket 71. By such a combination of pinion and gears, the number of revolutions of the shafts 72' and 73 is reduced to one-half of the standard number, and the sprocket 81 is enabled to maintain the standard number of revolutions by combination of the gears 79 and 80. The rotating power of the sprocket 81 is imparted through a chain 83 to a gear 85 secured to the input shaft 84 of the projector so that the rotation of the sprockets and shutter of the projector may be maintained at the standard number of revolutions.

The changeover type of projector in which either the standard-size film or the half-size film of the invention may be used, is designed to permit replacement of the above-mentioned parts of the projector.

FIGS. 18 to 20 show the half-size mask plate at the aperture; FIGS. 21 to 23 shows the standard-size mask plate at the aperture. 86 is the half-size mask plate, and 87 is its aperture; 88 is the standard-size mask plate and 89 is its aperture. These mask plates are replaceable with one another on the aperture. Moreover, they are designed in a similar manner as the film-driving sprocket, the driving sprocket in the sound-regenerating mechanism, and the slit member at the light-varying device and have respective members dimensioned to one-half the standard sizes, which are replaceable by the use of proper fitting elements.

According to the invention the film may be made thinner than that of the standard film as the amount of the film fed in unit time is reduced to a lesser extent than that of the standard film. Such film with a thin thickness may be applied to the half-size motion picture films aforementioned as well as to the following films of the present invention.

Further, according to the present invention, a positive film with a succession of positive frames in the standard size having four perforations per a frame may be produced by printing thereon from a negative film having a succession of negative frames in the half-size having two perforations per a frame.

On the contrary to the above, a positive film with positive frames in the half-size may be produced by printing thereon from a negative film having negative frames in the standard size.

For such methods there may be properly adapted lens systems and other detailed mechanisms which are described in the above-mentioned examples and well known in the industry.

The foregoing description relates to the present invention as embodied in the 35 mm. film, but the invention is certainly applicable to motion picture film of any other sizes. In addition, the proposed saving in the film can be achieved in any desired quantities other than 50 percent. The following clarifies this point.

FIGS. 24, 25, 26, 27 and 28 show motion picture film having different sizes of 8 mm., 16 mm., 35 mm., 65 mm., (the negative in this case), and 70 mm., respectively. FIG. 29 shows the motion picture film in 35 mm. reduced to one-third in size, and FIG. 30 shows the motion picture film in 70 mm. reduced to one-fourth in size.

The free changeover of projecting the motion picture film of either the standard size or the reduced size of the present invention may be possible in the invention as described above,

and a particularly preferable device for effecting such a changeover will be briefly explained hereinafter.

Explanation will be made in the case of the 50 percent or half-quantity saving example.

In order to reversibly change the number of revolutions transmitted from a driving motor M to the projecting mechanism, the following methods are applied.

1. As shown in FIG. 33, a gearbox V is provided between the motor M and the projecting mechanism PM, and the handle operation of the gearbox may vary the revolving speed of the projecting mechanism PM.

In this case, the number of revolutions of the motor is not varied.

2. As shown in FIG. 34, two motors M₁ and M₂ of the same type are provided side by side, pulleys P₁ and P₂ are equipped to the shaft of said two motors and are connected to each other by means of a belt (or teeth train, or chain wheels and chain), and the diameter of pulley P₁ is one-half of that of pulley P₂.

When electric current is supplied only to the motor M₂ and not to the motor M₁, then half-reduced revolutions may be transmitted to the projecting mechanism PM. On the contrary, when the electric current is supplied only to the motor M₁, then unreduced revolutions may be transmitted.

In this case, the number of revolutions may be varied simply by the changeover of the switch. It should be noted too that the number of revolutions of the motor is not varied.

3. The doubling of the number of poles of a stator of a motor reduces the number of revolutions of the motor to one-half. Then, if a changeover switch by which the electric current may be supplied either to all the poles or to half of the poles of the motor is provided, the number of revolutions of the motor may be reduced half by changing over the switch.

Each example of the invention applying the above methods is schematically shown in FIGS. 36 through 39.

FIG. 36 shows the example applying the above-mentioned 1.

Transmitting synchromotor 200 is directly connected to the driving motor M (24 revolutions per second), and receiving synchromotors 201A and 201B are connected to each driving shaft of the intermittent raking mechanism I and the shutter mechanism S respectively. 202 is a schematic drawing which shows the connection of the transmitting synchromotor and the receiving synchromotors. When a transmitting signal of the transmitting synchromotor 200 is transmitted to receiving synchromotors 201A and 201B to drive them with 24 revolutions per second, then the intermittent raking number of the intermittent sprocket is kept at 24 frames per second and the shutter is also kept at 24 revolutions per second, regardless of the variation of numbers of revolutions provided to the projecting mechanism (film-driving mechanism, etc.).

In this case, if the intermittent raking mechanism and the shutter mechanism are driven by one driving shaft, then only one receiving synchromotor is needed.

The electric connection of the transmitting and receiving synchromotors is shown by FIG. 5. This is of a three-pole type, and each corresponding pole is connected to each synchromotor by means of leading wires 202A, 202B and 202C.

FIG. 37 shows the example applying the above-mentioned method 2. Motors M₁ and M₂ (both 24 revolutions per second) are connected to transmitting synchromotors 200A and 200B, and the intermittent raking mechanism I and the shutter mechanism S are connected to receiving synchromotors 201A and 201B.

SW₁ is the switch by which the changeover of the connection between receiving synchromotor and either one of transmitting synchromotor of 200A or 200B may be made.

Now, when the switch SW₁ is ON as shown in the drawing, the power supply to motor M₁ causes the signal current of the transmitting synchromotor 200A, to be transmitted to receiving synchromotors 201A and 201B to drive them at 24 revolutions per second.

When the switch is changed over to supply power to motor M₂, half-reduced revolutions are transmitted to projecting mechanism PM but the signal current from transmitting synchromotor 200B is transmitted to the receiving synchromotors 201A and 201B to keep the standard speed of 24 revolutions per second of both the intermittent sprocket mechanism and the shutter mechanism.

FIGS. 38 and 39 show in detail the example shown in FIG. 33.

Due to the varied numbers of revolutions of motor M, the transmitting synchromotor should be adjusted mechanically and electrically.

FIG. 38 shows an example of the mechanical adjustment of the above.

15 A gearbox is provided between the motor M and the transmitting synchromotor 200.

When the revolutions of the motor M is reduced by half to provide half-reduced revolutions (12 revolutions per second) 20 to the projecting mechanism PM, it is required to operate the gearbox V to transmit the standard revolving number (24 revolutions per second) to the transmitting synchromotor 200.

25 For the electrical adjustment, without said gearbox, it is applicable to vary the poles connections between the transmitting and receiving synchromotors.

That is to say, if the number of rotators or stators of the transmitting synchromotor is double that of the receiving synchromotors, the number of poles used in the transmitting synchromotor being increased or decreased according to the number of revolutions of the motor, then the receiving synchromotor may be revolved at the constant speed. Ordinarily, the number of poles of stators is varied. FIG. 39 being an example of the above, the number of the poles of transmitting synchromotor is double that of the receiving synchromotor (six poles in this drawing), and among leading wires 202A, 202B . . . 202F connected to each pole, each two leading wires of each two poles which are positioned on a diagonal line, i.e., 202A and 202D, 202B and 202E, and 202C

35 and 202F, are made into one to be connected to each of three poles of receiving synchromotor 201, switch SW₂ being provided in leading wires 202A, 202C and 202E.

40 When the switch SW₂ is ON, the revolutions of the transmitting synchromotor 200 cause the revolutions of the receiving synchromotor 201 to be twice that of the former, and when this switch SW₂ is OFF, the revolution speeds of both synchromotors are the same due to the same number of the poles of each synchromotor. Therefore, when the revolution number of the motor is decreased by half, the turning on of the 45 switch SW₂ may keep the standard speed of 24 revolutions per second of the receiving synchromotor 201, and also maintain the standard speed of revolutions of the intermittent sprocket mechanism and the shutter mechanism. Furthermore, when necessary, it is easy to adjust the multiple proportions of poles of transmitting synchromotor and receiving synchromotor as three times, four times, and so on.

55 FIGS. 31 and 32 show the principle of the above as a practical example. This is of such type as was shown in the above-described embodiment shown in FIG. 36.

60 In FIG. 31, to the rear wall inside the gearbox 203 on one side of head machine 19 is supported a vertical axis 204 by means of blocks 205 . . . to the upper and lower ends of this axis are fixed helical gears 206 and 207. The gear 206 is engaged with the helical gear 209 fixed to the shaft 208 of the upper film-driving sprocket 62 and the other gear 207 is engaged with the helical gear 211 fixed to the shaft 210 of the lower film-driving sprocket. The helical gear 211 is engaged with the gear 212 fixed to the projecting-device power-transmitting shaft 84 and by such an arrangement power-transmitting shaft 84 to which the revolutions are transmitted from the motor M rotates the upper and lower sprocket shafts 208 and 210.

75 The receiving synchromotor to drive the intermittent sprocket 66 is constructed as follows.

To the front side of gearbox 203 is fixed a beam 213 with screws 214 . . . , to the rear wall of this beam 213 is fixed the receiving synchromotor 201A with screws 215 . . . , and the revolving shaft 216 of said synchromotor 201A is directly connected to the maltese cross driving shaft of the intermittent raking mechanism I. To the wall of the gearbox is fixed another receiving synchromotor 201B with screws 217 . . . , and the revolving shaft 218 of this receiving synchromotor is connected to the revolving shaft 219 of shutter 21 in the shutter mechanism S by means of coupling 220.

The revolving shaft 221 of the transmitting synchromotor 200 which is equipped to the front part of the driving motor M, is directly connected to the motor shaft, and leading wires 202A, 202B and 202C thereof are connected to above-mentioned receiving synchromotors 201A and 201B respectively.

The gearbox axis 222 of the gearbox V which is equipped to the rear part of the above-mentioned motor M extends into the sound head 223 to be connected to the shaft 224 of the worm 225. With this worm 225 is engaged worm gears 228 and 229 which are respectively fixed to shafts 226 and 227 of the film driving sprockets at the part of the sound head. A pulley 230 is fixed to said sprocket shaft 226 and a pulley 231 is fixed to said power-transmitting shaft 84 and both pulleys 230 and 231 are connected by means of a band 232 so that the revolutions from said gearbox may be transmitted to the sprocket of the sound head and the power-transmitting shaft 84 of the head machine.

A changeover lever 233 of the gearbox V is provided and has a cover 234, a supporting frame 235, an upper magazine 236 and a lower magazine 237.

In order to project the motion picture film of the standard size (frame dimensions: 22×16 mm.), the handle of gearbox V is positioned to obtain a standard speed 1 and the motor M rotates the film-driving sprockets 62 and 67 which drive the film at 27.4 m. per minute.

On the other hand, transmitting synchromotor 200 is simultaneously to provide a revolved, signal current which rotates receiving synchromotors 201A and 201B, so that the intermittent sprocket 66 may revolve at 24 frames per second and the shutter 21 may also revolve at 24 revolutions per second to project. In this case, the intermittent sprocket 66 has 16 teeth and the aperture 20 has its exposure window of having the standard dimensions of 22×16 mm. Furthermore in this case, the gearbox V may be removed.

In order to change over to projecting the half-size motion picture film (frame dimension: 22×8 mm.), the intermittent sprocket 66 with eight teeth (diameter being half), and the aperture 20 with its exposure window having the half-sized dimensions of 22×8 mm. are used.

When the handle 233 of the gearbox V is changed over to the position to obtain a half-speed and the motor M rotates the film-driving sprockets 62 and 67 by half the number of revolutions compared with the former example, the film is driven at 13.7 m. per minute. On the other hand, the transmitting synchromotor 200 makes, regardless of the decreased speed by the gearbox, 24 revolutions per minute, whose signal current causes the rotations of receiving synchromotors 201A and 201B by the same speed, so that the intermittent sprocket 66 may continue the intermittent raking of the film by the standard speed of 24 half-size frames per second and the shutter 21 may make the projection by the same speed of 24 revolutions per second as the former example.

The above is the explanation of the changeover between the standard and half-size motion picture films, but such designs as to the teeth number (and diameter) of the intermittent sprocket, as to the speed variation range of the gearbox, as to the poles number proportion of both transmitting and receiving synchromotors, and so on, may make it possible to change over among those motion picture films of a quarter-size, one-third size, and other various sizes.

By this device, the shutter mechanism is separately driven by the synchromotors, and is disconnected from the other projecting mechanisms with the beneficial results that a good

many gears may be abandoned, tear and wear may be decreased, the durability may be increased and the excellent projection with less dimmed images may be accomplished, and furthermore the operation of the equipment may be more easily facilitated with less control and maintenance, like cleaning, and with less noise.

Since an easy changeover at the various sites (movie theatres, etc.) is required, the record-regenerating device will be explained hereafter which may optionally regenerate the recording of motion picture films of the standard size and the shortened size and which are provided with an optical soundtrack or magnetic soundtrack thereon.

A frame 19' of the projecting mechanism is provided with sprockets 62 and 67 which drive the film at a constant speed, the intermittent driving sprocket 66, an aperture 114, a projecting lenses cylinder L, a shutter 21 and a projecting lamp house La. A lower record-regenerating mechanism house 309 is connected to said frame and is provided with constant speed driving sprockets 310 and 311, a sound wheel 312, an exciter lamp 313, a slit lenses cylinder 314 and some with well-known components. To the top of the above-described frame 19' is connected the upper record-regenerating mechanism house 316 through an adapter plate 315 with screws 317 . . . or like that, and to the top of said house 316 is fixed the magazine 318.

The above-described upper record-regenerating mechanism is constructed as follows.

Referring to FIG. 41, a sprocket 319 is rotatably mounted on the shaft 320 fixed to the house, and rollers 321 and 322 on both sides of the sprocket are fixed, in such a manner as to permit the free rotations, to shafts 325 and 326 at the ends of arms 323 and 324. Shafts 327 and 328 of the root ends of the arms are supported in box 329 containing silicon grease therein which is fixed on the rear wall of the house, and are equipped with spiral springs 330 and 330 in the box, so that said rollers 321 and 322 may be pistoned into the corresponding inside.

The axis 332 of sound wheel 331 is rotatably supported at one end to the house and the other end of the axis 332 is fixed to a flywheel 333 and one side of the sound wheel is equipped with a photodiode 334 or a phototube.

A slit lenses cylinder 355 is fixed at the symmetrical position to said sound wheel, and an exciter lamp 336 is inserted in the sprocket 339 which is fixed to the bracket 327 through a spring 328.

A magnetic record-regenerating head 340, whose fixing members 344 and 344 are fixed in such a manner as to permit the free fixing and removal of the head, is connected to the house at the left lower part of said sound wheel with a screw 341.

The head is provided with a front magnetic shield 342 and a rear magnetic shield 343. In another way, as shown in FIG. 44, a slot 345 is provided to fixing members 344 and 344 of said head, and a screw 341 is screwed through this slot so that the head 340 may be touched to the film along the said slot 345 at the time of using the head, the head on the contrary being possibly detouched therefrom at the time of nonuse.

A pair of guide rollers 346 and 347 are fixed to the front side of said sprocket 319 in such a manner as to permit their free rotation. Rollers 348 and 349 are fixed to the rear part of said rollers 321 and 322 in such a manner as to permit free rotations, and a roller 350 is supported to the top end of arm 351 in the same manner as above, the root end of said arm being fixed to axis 352 in such a manner as to permit free rolling.

The upper magazine 353 is fixed to the top of the upper regenerating mechanism house 316 with a screw 355 through an adapter plate 354 in the same way as above. 356 is a pat roller of the magazine.

The motion picture film 1 withdrawn from the upper magazine 353 is driven to the top side of the sprocket 319 through the guide roller 346, driven to the sound wheel 331 through rollers 321, 348 and 350, driven to the lower side of

said sprocket 319 through rollers 349 and 322, and then led into the projecting mechanism frame 19' through the guide roller 347, and thereafter driven up to the constant speed driving sprocket 68 in the same manner as the conventional one, and finally taken up by the revolving reel of the lower magazine 318 after passed through the lower regenerating mechanism house 319. Upon operating the projecting equipment, the film 1, passed through the said upper regenerating mechanism, is withdrawn at a constant speed by means of the revolutions of the constant speed driving sprocket 62, the film itself then revolving the sprocket 319 whose revolutions withdraw the proceeding part of the film from the said magazine 318, so that both parts of the film driven in the reverse directions about the sprocket 319 may keep the same speed and then the speed and tension of the film at the part of the sound wheel may be constant.

FIG. 46 shows another example of the above-described upper mechanism.

Instead of one sprocket in the above example, two sprockets 319 and 319' are provided and the gears 357 and 357', provided to shafts 320 and 320' of those sprockets, are engaged with each other. Furthermore, rollers 325, 326 and 350 with arms in the above example are replaced by a roller 350' with a flywheel 358, and the position of the magnetic regenerating head 340 is moved to the upper part of the housing.

In the case shown by above FIG. 41, such a device, wherein each member is positioned symmetrically about the center of the sprocket 319 may also be made. This time, it is preferable to support the magnetic head 340 to the arm so as to touch the inside of the film.

Hereinafter is explained the projecting of the reduced-size motion picture film with the optical soundtrack by means of this device.

The soundtrack of the half-size film is recorded about 20 frames behind the projected part of the film in order to synchronize the images and the sound, since the sound is regenerated by the upper regenerating mechanism.

The adjustment between the intermittent raking and the film-driving speed is made by any of above-mentioned methods. The exciter lamp in the lower regenerating mechanism is turned OFF this time.

The half-size film set inside the upper magazine is driven to the lower magazine through the upper regenerating mechanism, the projecting mechanism and the lower regenerating mechanism (unoperated), to be projected.

When it is desirable to project the standard-size motion picture film with the optical soundtrack, the film is directly withdrawn into the projecting mechanism without passing through the sprocket 319 in the upper regenerating mechanism, the lower regenerating mechanism being operated. Each sprocket in the projecting mechanism has the standard diameter. In another way, it is applicable to to fix the upper magazine 318 to the frame 19' as in the conventional one, without the upper regenerating mechanism house 316 which may be removed by unscrewing the adapter plate 315.

Next, in case of projecting the motion picture film with the magnetic soundtrack, the magnetic regenerating head 340 is fixed in the position where it contacts the film, others being adjusted according to the above example.

In case of projecting the standard-size motion picture film with both magnetic and optical soundtracks, the upper regenerating mechanism operates the magnetic record regeneration and the lower regenerating mechanism simultaneously operates the optical record regeneration.

The projection of the half-size motion picture film with both the magnetic and optical soundtracks may be made by the same way as above except the above-mentioned necessary adjustments.

Thus, the present invention makes it possible and practical to project any of such various types of motion picture films as those of the standard size or the half-size with the optical or magnetic soundtrack, which is easily adaptable to the conventional projecting equipments.

As has been described above, according to the invention, the vertical dimensions of the film may be shortened to one-half or less, with the result that in producing a film that previously required 30,000 feet of raw film, the present invention enables 15,000 feet of raw film to be sufficient, and accordingly, a 50 percent saving is achieved both in large number of positive films in the original one negative film. Remarkable saving follows also in developing, printing and other processes before and after said processes along with the materials to be used in all such processes. Moreover, in case of a motion picture film requiring an hour and 40 minutes for projection, the previous 10 reels of film 2,740 m. in length may be decreased by this invention to five reels of film 1,370 m. in length, and the frequency of replacing reels may be reduced from nine times to four times, resulting in lesser damage to the film caused by handling, smaller transporting cost of the film due to a much reduced weight, and the alleviation of the current overwork shouldered by the people related with the motion picture industry. In other words, since this invention enables the motion picture to be manufactured with half or even less than half of the previous consumption of raw film, negative film, positive film, reverse film etc., resulting in vast savings in material costs, labor costs, silver costs, and other manufacturing costs together with the reduction of the film feed speed and others, the prevention of consumption of machinery, and the avoidance of such troubles as the replacement of reels of film. The space for storing films can be remarkably saved. In addition, the above-described positive film can also be used for slides and any other viewing apparatuses without screen projection.

According to the invention, clearer images may be obtained on the wide screen without using the anamorphic lens.

Furthermore, the equipment proposed by this invention can be handled easily and readily with those familiar with present-day equipment.

Though the foregoing description of the invention has been made at considerable length, the details involved have been necessitated simply for easy comprehension, so that it is to be fully understood that any modification or change other than the illustrated specific embodiment and constructions may be made according to the spirit and scope of this invention.

What I claim and desire to secure by letters patent is:

1. A photographic process comprising: providing a strip of raw film having a longitudinal axis; exposing said strip of raw film to produce thereon successive, anamorphic latent images each compressed only in the direction of said longitudinal axis of a photographed field with substantially no spacing therebetween; developing said raw film to obtain negative film having said successive, anamorphic images compressed in only one direction thereon with substantially no spacing therebetween; and printing the negative film to obtain a positive film having said successive, anamorphic images compressed in only one direction thereon with substantially no spacing therebetween.

2. A process according to claim 1; wherein said successive, anamorphic images compressed in said direction of said longitudinal axis have one dimension a predetermined number of times greater than another dimension.

3. A process according to claim 1; wherein said successive, anamorphic images compressed in said direction of said longitudinal axis are rectangular and have the larger dimension a predetermined number of times greater than the smaller dimension.

4. A process according to claim 3; wherein said larger dimension is equal to twice said smaller dimension.

5. A process according to claim 3; further including the step of projecting said successive, anamorphic images compressed in said direction of said longitudinal axis contained on said positive film at a speed proportional to said predetermined number.

6. A process according to claim 5; wherein said step of producing successive, anamorphic latent images compressed in said direction of said longitudinal axis includes compressing

given-sized images and wherein said step of projecting successive, anamorphic images compressed in one direction includes restoring said successive, anamorphic images compressed in said direction of said longitudinal axis to their uncompressed size wherein they represent a replica of said photographed field.

7. A process according to claim 5; wherein said step of projecting at a speed proportional to said predetermined number comprises projecting at a speed inversely proportional to said predetermined number.

8. A process according to claim 1; further including the step of projecting said successive, anamorphic images compressed in said direction of said longitudinal axis contained on said positive film at a speed proportional to the amount said successive, anamorphic images are compressed.

9. A process according to claim 8; wherein said step of producing successive, anamorphic latent images compressed in said direction of said longitudinal axis includes compressing given-sized images and wherein said step of projecting successive, anamorphic images includes restoring said successive, anamorphic images to their normal, uncompressed size wherein they represent a replica of said photographed field.

10. A photographic process for producing wide screen pictures comprising: producing successive, substantially undistorted latent images compressed equally in two perpendicular directions of an elongated photographed field on a raw film with substantially no spacing between successive images, each image having one dimension a predetermined number of times greater than another dimension; developing said raw film to obtain negative film having said successive, substan-

tially undistorted images compressed equally in two perpendicular directions thereon with substantially no spacing between successive images; and printing said negative film to obtain positive film having said successive, substantially undistorted images compressed equally in two perpendicular directions thereon with substantially no spacing between successive images.

5 11. A process according to claim 10; wherein said successive, substantially undistorted images compressed equally in two perpendicular directions are rectangularly shaped.

12. A process according to claim 11; wherein said larger dimension is equal to twice said smaller dimension.

13. A process according to claim 10; further including projecting on a screen said successive, substantially undistorted images compressed equally in two perpendicular directions contained on said positive film to obtain a wide screen replica of said elongated photographed field.

14. A process according to claim 13; wherein said step of producing successive, substantially undistorted images compressed equally in two perpendicular directions comprises focusing successive images of said elongated photographed field on said raw film by an optically aligned wide conversion and spherical lens system; and wherein said step of projecting said successive, substantially undistorted images compressed equally in two perpendicular directions comprise focusing said successive images contained on said positive film by an optically aligned spherical and wide conversion lens system onto a screen to obtain a wide screen replica of said photographed field.
